CANDLEHOLDER

Frederick D. Lowell, 608 S. Dearborn St., Chicago, Ill.

Filed Mar. 30, 1959, Ser. No. 55,254

Term of patent 14 years

(Cl. D48—2)

Fig. 1 is a top plan view of the candleholder showing my new design;

Fig. 2 is an elevational view of the candleholder shown in Fig. 1;

Fig. 3 is a sectional view taken along line 3—3 in Fig. 1; and

Fig. 4 is an enlarged fragmentary sectional view taken on line 4—4 of Fig. 1.

The characteristic feature of my design for the candleholder disclosed resides in the specific pattern on the top surface as best shown in Fig. 1.

I claim:

The ornamental design for a candleholder, substantially as shown and described.
